METHOD OF AND APPARATUS FOR WIND-
ING SPHERES

Hiram N. Huse, Providence, R. I.

Application February 11, 1942, Serial No. 430,381

25 Claims. (Cl. 242—3)

This invention is directed to machines for winding spheres, and has for its primary object the provision of a construction whereby in the winding operation a true sphere will be produced, the coverage pattern being uniform throughout the entire sphere. The machine of this invention is adapted to the winding of spheres of all types, but is particularly well suited to the winding of golf balls wherein rubber thread, wound under considerable tension, is employed in the making of the ball. I make this reference to golf balls because of the fact that it is extremely desirable in the manufacture of golf balls that the coverage pattern be uniform and a perfect sphere produced.

Another object of my invention is the provision of a construction whereby the sphere is held between two heads, one at least of which is rotated about the axis of the machine, the heads being provided with rollers some of which are positively driven, variable speed mechanism being provided whereby the speed of rotation of the driven rollers is varied as the sphere diameter increases. By such a construction in the winding of a sphere the speed of the driving rollers is increased in direct and constant ratio to the increase in the size of the sphere being wound. In this way I obtain a more nearly perfect sphere that has been possible with winding machines as heretofore constructed and a better and more perfect distribution of the winding thread so that at all diameters the coverage pattern is the same.

In the accompanying drawings:

Fig. 1 is a sectional elevational view of one embodiment of my invention;

Fig. 2 is a section on the line 2—2 of Fig. 1;

Fig. 3 is a section on the line 3—3 of Fig. 1;

Fig. 4 is a section on the line 4—4 of Fig. 1;

Fig. 5 is a fragmentary elevational view of another embodiment of the invention; and

Fig. 6 is a sectional elevational view of still another embodiment of my invention.

Referring to the drawings in detail and with respect, first of all, to Figs. 1 to 4, inclusive: 2 designates the frame of the machine, which is provided with lateral extensions or offsets 4 and 6 that are vertically spaced from each other. The winding heads are mounted in these two offsets.

Mounted for rotation in the offset 6 is a driven winding head 8. As illustrated this head is driven about a vertical axis.

10 designates a quill constituting the drive

shaft for the driven winding head, and 12 designates the antifriction bearings for the head.

Keyed to the lower end of the drive shaft 10 is a gear 14 constantly meshing with gear 16 on the vertically extending shaft 18 which carries a drive pulley 20 at its lower end constituting the main drive for the machine.

Extending upwardly within the drive shaft 10 is a hollow cam-driving shaft 22. The lower end of this shaft 22 projects below the lower face of the gear 14 and has a gear 24 keyed thereto, this gear meshing with gear 26 also on the shaft 18. The gears 14 and 24 while on the same centers are unequal gears, the gear 14 having a higher peripheral speed than the gear 24.

Carried by or formed on the inside of the gear 24 is a yoke 28, best illustrated in Fig. 4, and providing supports and bearings for three gimbals 30. Each of these gimbals provides a bearing for friction drive rollers 32 which may be made of rawhide, fiber or other suitable material.

Each gimbal 30 is provided with a rigid arm or lever 34, the outer end of each of these levers being pivoted to a link 36, the lower ends of which links are secured to a collar 38 mounted on ball bearings 40 for rotation about a stub shaft 42 mounted vertically in the lower part of the machine frame. The stub shaft 42 is in vertical alignment with the quill shafts 10 and 22 and in the vertical axis of the machine.

Extending upwardly within the quill shaft 22 is a roller-assembly drive shaft 44 and keyed to the lower end of this shaft is a cup-shaped friction disc 46. The friction drive rollers 32, above referred to, engage the upper face of this disc to drive the same and thereby impart rotation to the roller drive shaft 44.

The friction driving rollers 32, as above pointed out, are mounted in the gimbals 30 and if the collar 38 carried by the shaft 42 be moved upwardly it will be quite apparent that the rollers will be tipped or pivoted from the full line position shown in Fig. 1, for instance, to the dotted line position in the same figure and which I will designate 32'. By the same token if the collar 38 be moved downwardly with respect to the stub shaft 22 the rollers will be tipped the other way as indicated at 32''.

50 This pivoting or adjusting of the rollers 32 will of course vary the speed of rotation of the friction disc 46 and in turn vary the speed of rotation of the shaft 44.

The gear 24 is cut through to accommodate 55 these rollers, as seen in Fig. 1, for instance, so as

to allow the rollers to contact the underface of the gear 14. It will be understood of course that the friction between the gear 14, the rollers 32 and the driving disc 46 will rotate the driving disc. Consequently, the rollers 32 being adjustable the speed of rotation of the disc 46 may be varied without varying the speed of the gear 14.

Reverting to the winding head 8: The upper end of the roller drive shaft 44, above referred to, carries a gear 48 meshing with gears 50 and 52 mounted on vertically extending stub shafts 54 and 56, respectively, so that rotation of the roller drive shaft 44 will drive the gears 48, 50 and 52.

On the upper end of each of the vertically extending stub shafts 54 and 56 is a bevel gear 74, each meshing with a bevel gear 76 which is on the shaft 78 of each of the spherical driving rollers 80. These shafts 78 are inclined to the axis of the stub shafts. I have shown this inclination as a 45° angle but it is to be understood this is illustrative only. The driving rollers 80 engage directly the sphere being wound and being positively driven will rotate the sphere.

In the upper end of the roller drive shaft 44 is a pin or stub shaft 58 carrying a wide faced gear 60 meshing with a gear segment 62 carried by a pivoted cam lever 64, this lever being pivoted on cam lever shaft 66, the wide faced gear 60 meshing also with gear 79 on the mount 81 for the rollers 80. The cam lever 64 carries a cam follower roller 68 which follows a cam track 70 in cam 72, the latter being mounted upon or integral with the upper end of the vertically extending cam drive shaft 22. Actuation of the cam 72, by drive shaft 22, will actuate gear segment 62 which motion through wide faced gear 60 will impart rotation to the mount 81 in bearing 83, so that the driving rollers 80 will be moved bodily about an axis parallel to the axis of rotation of the head 8 first in one direction and then in the opposite direction to vary the angle of movement otherwise imparted to a sphere being wound by rotation of head 8 and rotation of the rollers 80 on their individual axes.

In the drawings the machine stands vertically, and the winding head above described is the lower head of the machine.

With respect to the cooperating upper head: It will be seen from Fig. 1 that this head comprises a single roller 84. This is an idler roller ball bearing mounted on the lower end of a vertically extending shaft 86 which is rotatable in bearings 88. The center line of the shaft 86 passes through the center of the roller.

The shaft 86 and the roller 84 carried thereby are vertically adjustable in accordance with increase in the sphere diameter through automatic adjusting mechanism which will be described later on. At the upper end of the vertically adjustable supporting structure for the shaft 86 I provide a weight 90. This weight is for the purpose of maintaining the driving rollers 80 and 82 of the lower winding head and the idler or backing roller 84 of the upper head in contact with the sphere throughout the winding operation.

Mounted on the shaft 86 and freely rotatable thereon is a gear 92 driven by gear 94 carried on the upper end of the shaft 18, which as above pointed out is the drive shaft for both the lower and upper heads. The gears 92 and 94 are the same size as and on the same centers as the gears 14 and 16. The shaft 18 also carries a gear 96 at its extreme upper end which is in alignment with and is the same size as gear 26 and meshes

with a toothed cam 98 mounted for free rotation on the shaft 86. This cam is the same diameter as the gear 24. Keyed to the shaft 86 intermediate the cam 98 and the gear 92 is a gear segment 100. A rack gear 102 meshes with the gear segment 100. This rack is pivoted as shown at 104 on the gear 92 and is equipped with cam follower 106 which follows the cam 98.

The shaft 86 makes the same number of revolutions per minute as the lower winding head 8, and the cam mechanism just described is provided to keep the axis of the idler roller 84 in constant parallelism with the axes of rollers 80 on the lower winding head and has the same relation to idler roller 84 as the cam 72 has to the rollers 80. It will be apparent from the foregoing that so far as the roller 84 and the rollers 80 are concerned, the former is an idler while the latter are drivers.

As was pointed out at the outset of this description one of the objects of this invention is to provide variable speed mechanism whereby the speed of the driving rollers 80 on their individual axes will increase in direct and constant ratio to the increase in the size of the sphere being wound. In this same connection: The bearing 88 for the shaft 86 of the upper winding head is carried in a vertically movable sleeve 108 which is extended upwardly to provide a mount or support for the weight 90 already referred to. This extension of the sleeve is equipped with a pin 110 engaging a fork in the bifurcated end of a lever 112 which is pivoted on the frame 2 of the machine, as shown at 114. Rigid with the lever 112 is a lever 116. At the lower end of the machine the mount for the collar 38 is provided with a pin 118 cooperating with a pivoted lever 120. The lever 120 is rigid with lever 122 in turn connected to link 124 which is adjustably connected to the lever arm 116 as shown at 126. Not only is the end of the link 124 adjustable in the lever 116 but the link 124 may be shortened or lengthened by reason of the provision of the turn-buckle 130.

While the shaft 86 moves upwardly as just described due to the increase in the sphere diameter, and while the speed of the roller-assembly drive shaft 44 is varied at the same time, the idler roller 84 only rotates by reason of its engagement with the sphere being wound. The speed of the driving rollers 80, however, is positively varied due to the fact that they are driven by the shaft 44 whose speed is varied as above explained because of the constantly increasing sphere diameter.

The winding thread which is to constitute the sphere being wound is designated 132 and it will be understood that in practice this thread is started on a center of some kind which may be merely a knot in the end of the thread or it may be any one of the various types of centers that are employed, for example, in winding golf balls.

For the purposes of description I will assume that 134 represents the beginning or start of the winding of the sphere. I have assumed this condition because in the drawings I have shown the heads in contact with the surface of 134.

For the purposes of this description, therefore, the friction rollers 32 are in the full line position shown in Fig. 1 of the drawings and the main drive shaft 18 is being rotated in the direction of the arrow on this shaft. Under these conditions the drive quill shaft 10, the cam drive shaft 22 and the roller drive shaft 44 are rotating clockwise at a speed depending upon the

gear ratio between the gears 16 and 14 and between the gears 26 and 24. Likewise the cam 98 and the gear 92 of the upper winding head are rotating clockwise so that through the gear segment 100 and rack gear 102 the shaft 86 will be driven in a clockwise direction also.

Rotation of the shaft 44 will impart movement in an anti-clockwise direction to the shafts 54 and 56 carrying the bevel gears 74, this motion being transmitted to the bevel gears 76 to rotate these gears in a clockwise direction so that each spherical driving roller 80 is rotated in a clockwise direction, as viewed in Fig. 1, on its own axis. Inasmuch as the spherical driving roller 80 is at this instant being rotated in the proper direction due to the rotation of the upper driving shaft 86 the center 134 will be rotated about an axis which is parallel to the axes of rotation of the rollers 80 and 84.

It will be seen therefore that the thread 132 will be applied to 134 along various great circles of the same.

In addition to the movement of the driving rollers above described the mount 81 therefor is rotated about a vertical axis through the gear segment 62 and cam 72, so as to vary the angle of movement otherwise imparted to the sphere being wound. This will give a fair sphere but better results are obtained through the variable speed mechanism above described. As the sphere 134 increases in diameter the shaft 86 moves upwardly, which rocks the friction rollers 32 on a horizontal axis so that the upper part of these friction rollers will be shifted toward the periphery of the gear 14 and the lower part toward the center of cup-shaped friction disc 46. For example, we might assume that the shift is from the full line position shown in Fig. 1 to the dotted line position designated 32''. The cup-shaped friction disc 46, it will be remembered, is keyed directly to the shaft 44; consequently the disc 46 will, under these conditions, be speeded up to increase the speed of the shaft 44 and hence in the last analysis increase the speed of the driving rollers 80. In other words, the peripheral speed of the sphere being wound increases in direct proportion to the increase in the sphere's diameter so that a theoretically perfect sphere is produced.

In further explanation of the desirability of varying the speed of the driving rollers 80 as the sphere being wound increases in diameter: Let it be assumed for the moment that the speed of the rollers 80 is constant. Under such conditions the rollers 80 would space off a given dimension, say one-quarter inch between wraps. The spacing would be the same regardless of sphere size. On a small sphere the quarter-inch wraps would be spaced once around the sphere. This would be the case only at one size of sphere, it being very apparent that, if the speed of the rollers 80 is not varied, a point would be reached as the sphere diameter increases where the same number of wraps would be insufficient to cover the sphere periphery, or expressing it another way would not go as far around the sphere. It is very evident that it becomes desirable to space the threads further apart with increase in the diameter of the sphere being wound or, in other words, there should be a definite ratio between the wrap spacing and the sphere diameter. It will be very apparent, in the light of the above explanation, that in my improved construction by increasing the speed of the rollers 80 in direct proportion to the increase in

the sphere diameter the wrap spacing will be varied accordingly and in definite ratio to this varying diameter, so that the coverage pattern is the same at all sphere diameters.

5 In the embodiment of the invention as illustrated in Fig. 5, the two winding heads 8' are identical with the head 8 of Fig. 1. It will be understood that in this form of my invention the variable speed mechanism of Fig. 1 will be employed, the connection of this mechanism to both heads being a duplicate of the connection to the head 8 of Fig. 1.

10 Here again it will be appreciated that the speed of the driving rollers, which in this instance will be in both heads, is increased in direct proportion to the increase in the diameter of the sphere being wound.

15 While the construction so far described in detail produces excellent results so far as the production of a true sphere is concerned in comparison with prior machines, I find that even better results are obtained if a valuable drive be provided for the cam 72 which rotates the mount 81 for the driving rollers 80 about an axis parallel to the main axis of the machine. For this purpose I provide the construction illustrated in Fig. 6.

20 From an inspection of this figure of the drawings it will be seen that the same comprises much of the same mechanism as illustrated in Fig. 1 and corresponding parts in Fig. 6 have been given the same reference characters as employed in Fig. 1 so that a description of the entire machine of Fig. 6 will be unnecessary. In other words, in 25 the construction illustrated in Fig. 6 I have retained the feature of varying the speed of the shaft 44 and hence the speed of rotation of rollers 80 on their own axes in accordance with the increase in diameter of the sphere being wound.

30 In this embodiment of my invention I go further in that I vary the speed of rotation of the cam 72, that is to say, the speed of rotation of the shaft 22 in accordance with the variation in the diameter of the sphere being wound.

35 Referring specifically to Fig. 6: 18 designates the drive shaft and 150 an intermediate shaft. On the lower end of this intermediate shaft and rigid with it is the gear 26 which, as before, meshes with the gear 24. The gear 16 which, as

40 before, meshes with 14 is loosely mounted on shaft 150. The gear 16 also meshes with a gear 152 which is rigid with the drive shaft 18. On the upper end of the drive shaft 18 I provide gears 154 and 156 each of which is rigid with this shaft. The gear 154 meshes with the gear 94 which as

45 in Fig. 1 is in mesh with the gear 92. The gear 94, however, is now mounted on shaft 150 on which it is freely rotatable. The gear 156 meshes with a gear 158 freely rotatable on shaft 150. The gear 96 which, as in the case of Fig. 1, meshes with the gear 98 is fixedly mounted on the shaft 150. Inasmuch as the gear 96 is fixed to the shaft 150 while the gear 94 is rotatable with respect to the shaft 150, and inasmuch as the gear 16 is free

50 on 150 but in mesh with the gear 152 fast on the drive shaft 18, while the gear 26 is fast on the shaft 150, it will be quite apparent that this embodiment of my invention provides for variations in the drive for the sphere 134 being wound just as in the embodiment of the invention as illustrated in Fig. 1.

55 In Fig. 6, however, the shaft 150 is provided with a vertically slidable collar 160, the pin 162 of which engages one arm of a lever 164 pivoted at 166. A link 168 extends from the lever 164 to

the lever 120. It will be apparent, therefore, that the movement of 120, described in connection with Fig. 1, will impart similar movement to 164 and hence to the collar 160.

The gear 158 above referred to, which is free to rotate on the shaft 150 and meshes with the gear 156 on the drive shaft 18, engages friction rollers 170 which are similar to the rollers 32, these rollers engaging a disc 172 which is keyed to shaft 150.

The rollers 170 are provided with arms 174 and 176 similar to the arms 34 and 36, the arms 176 being connected to the collar 160 which, as above pointed out, is slideable vertically of the shaft 150.

The disc 172 as well as the gear 26 which drives the gear 24 being keyed to the shaft 150 and the gear 24 being keyed to the shaft 22 which drives the cam 72, it will be quite apparent that if the speed of the disc 172 be varied to vary the speed of the shaft 150 the speed of rotation of the cam 72 likewise will be varied.

Through the connection of the rollers 170 to the lever 120 it will be obvious that as the sphere 134 being wound increases in size, the collar 160 will be moved downwardly of the shaft 150 to tip the rollers 170, from the full line position shown, toward the center of the disc 172 to increase the speed thereof. This increase in speed of 172 will be imparted to the cam 72 so that we therefore have an arrangement whereby the speed of the cam 72 is varied in accordance with the increase in the diameter of the sphere 134 being wound. Inasmuch as the gear 96 which is geared to the cam 98 is fast on the variable speed shaft 150, it will be apparent that the speed of the cam 98 is varied in the same manner as that of the cam 72 in accordance with the increase in the diameter of the sphere 134 being wound.

In this embodiment of my invention, therefore, it will be appreciated that not only do I vary the speed of rotation of the driving rollers for the sphere being wound, as the sphere increases in diameter, but I also vary the movement imparted to the rollers by the cams 72 and 98 in accordance with the increase in diameter of the sphere being wound, so that in the finished sphere I have a theoretically perfect sphere in which the wound pattern is uniform at all sphere diameters.

It is to be understood that changes may be made in the details of construction and arrangement of parts hereinabove shown and described within the purview of my invention.

What I claim is:

1. In the winding of spherical bodies, the method which comprises effecting rotation of the sphere on its own axis during the winding operation, the speed of rotation of the sphere gradually increasing as the diameter of the sphere increases.

2. In the winding of spherical bodies, the method which comprises effecting rotation of the sphere on its own axis as the same is being wound, the speed of rotation of the sphere being increased in fixed ratio to the gradually increasing diameter of the sphere.

3. In a machine for winding spherical bodies, the combination of opposed winding heads, one of which is equipped with a rotatable driving member engaging the sphere being wound to present different parts of the surface of the sphere to the point of winding, and means for varying the speed of said driving member in fixed ratio to the constantly increasing diameter of the sphere.

4. In a machine for winding spherical bodies,

the combination of opposed winding heads, one of which is equipped with a spherical driving member for constantly engaging the surface of the sphere being wound to present different parts of the surface of the sphere to the point of winding, and means for driving said spherical driving member at a speed which increases in fixed ratio to the constantly increasing diameter of the sphere.

5. In a machine for winding spherical bodies, the combination of opposed rotatable winding heads, one of which is equipped with a rotatable driving member constantly engaging the sphere being wound to rotate the same thereby to

15 present different parts of the surface of the sphere to the point of winding, and a drive for said driving member controlled by the sphere being wound and operable to accelerate the driving member in fixed ratio to the constantly increasing sphere diameter.

6. In a machine for winding spherical bodies, the combination of opposed winding heads, one of which is equipped with a rotatable driving member constantly engaging the sphere being wound to rotate the same and thereby present

25 different parts of the surface of the sphere to the point of winding, one of said heads receding from the other as the sphere diameter increases, and control mechanism operated by said head movement to vary the speed of rotation of the rotatable driving member in fixed ratio to the sphere diameter.

7. In a machine for winding spherical bodies, the combination of opposed winding heads, one of which is equipped with a rotatable driving member in constant engagement with the sphere being wound to rotate the same, a drive for said rotatable driving member, one of said heads being moved away from the other by the sphere as the diameter of the latter increases, and a control for said drive actuated by the said recession of the winding head to effect an increase in the speed of the said rotatable driving member as the sphere diameter increases.

8. In a machine for winding spherical bodies, the combination of opposed rotatable winding heads, rotary sphere gripping means carried by said heads, and a variable speed drive for rotating the gripping means of one head about an axis which is angularly disposed with respect to the axes of rotation of the heads, said drive varying the speed of rotation of the gripping means in fixed ratio to the increasing diameter of the sphere being wound.

9. In a machine for winding spherical bodies, the combination of opposed winding heads, an idler roller carried by one head, a driven roller carried by the other head, the sphere being wound being gripped between said rollers, driving means for rotating one of said heads, driving

60 means for rotating said driven roller about an axis angularly disposed with respect to the axis of rotation of the rotatable head, a shaft on which the idler roller is mounted and driven off the first mentioned driving means whereby the axis of rotation of the idler roller will be maintained in parallelism with the axis of rotation of the driven roller throughout the winding operation.

10. In a machine for winding spherical bodies, the combination of opposed winding heads, sphere gripping rollers carried by the heads, and a variable speed drive for the rollers of one head, said drive comprising a drive shaft, a disc carried thereby, and rollers engaging said

disc to drive the same, and a connection between the rollers and the sphere being wound whereby as the sphere increases in diameter it will shift the rollers radially of said disc to vary the speed of the same in direct ratio to the increase in the sphere diameter.

11. In a machine for winding spherical bodies, the combination of opposed winding heads, sphere gripping rollers carried thereby, means for rotating one of said heads whereby the sphere being wound is constantly rotated on a single axis, an intermittent drive for the rollers of the rotating head for intermittently rotating the sphere about an axis angularly disposed with respect to said first mentioned axis, said intermittent drive being controlled by the sphere being wound so that its speed is increased as the sphere diameter is increased, whereby the coverage pattern will be the same at all sphere diameters from minimum to maximum.

12. In a machine for winding spherical bodies, the combination of opposed winding heads, sphere gripping rollers carried thereby, means for rotating one of said heads whereby the sphere being wound is constantly rotated about a single axis, an intermittent drive for the rollers of one head for intermittently rotating the rollers about an axis which is at an angle to the first mentioned axis, a drive for the other head whereby the roller of that head may always rotate about an axis parallel to the said angularly disposed axes of the rollers of the first head, and a driving connection between the sphere being wound and the intermittent roller drive whereby the speed of the intermittent drive will be increased automatically in fixed ratio to the increasing diameter of the sphere, so that the coverage pattern on the sphere's surface will be the same throughout the sphere from minimum to maximum diameters.

13. In a machine for winding spherical bodies, the combination of opposed winding heads equipped with sphere gripping rollers for gripping the sphere being wound, one of said heads being bodily movable so as to be forced away from the other by the sphere as the diameter of the latter increases, a drive for rotating one of said heads thereby to rotate the sphere being wound about the same axis, a drive for intermittently rotating the sphere about another axis, and a connection between the said bodily movable head and the last mentioned drive for varying said drive to increase the intermittent rotation of the sphere being wound in fixed ratio to the gradually increasing sphere diameter.

14. In a machine for winding spherical bodies, the combination of opposed winding heads, rollers carried by said heads for engaging a sphere being wound, a variable drive for rotating the rollers of one head about their own axes at a speed dependent upon the diameter of the sphere being wound, a mount for said driven rollers, and a drive for said mount which varies in accordance with the diameter of the sphere being wound.

15. In a machine for winding spherical bodies, the combination of rotatable opposed winding heads, rollers carried thereby for engaging and rotating a sphere being wound, a mount for the rollers of one head, means for rotating this mount on an axis parallel to the axis of rotation of the head, first in one direction and then in the opposite direction, said last mentioned means being varied in fixed ratio to the varying diameter of the sphere.

16. In a machine for winding spherical bodies, the combination of opposed winding heads, rollers carried thereby for engaging a sphere being wound, means for rotating one of said heads, means for rotating the rollers of said last mentioned head about axes angularly disposed with respect to the axis of rotation of the head, a mount for said rotatable rollers, and a drive therefor for rotating said mount about an axis parallel to the axis of rotation of the head, said drive being varied in accordance with the constantly increasing diameter of the sphere being wound.

17. In a machine for winding spherical bodies, opposed winding heads, sphere engaging rollers carried thereby, a mount for the rollers of one head, a drive for rotating the mount independently of rotation of the rollers, said drive including a rotatable cam, and a connection between the last mentioned head and said drive to vary the latter, thereby to vary the speed of said cam in accordance with variations in the diameter of the sphere being wound.

18. In a machine for winding spherical bodies, opposed winding heads, one of which recedes from the other as the sphere being wound increases in diameter, sphere engaging rollers carried by said heads, a mount for the rollers of one head, a drive including a cam for rotating said mount intermittently about an axis parallel to but offset with respect to the axis of the last-mentioned head, and a connection between the last mentioned head and said drive to vary the latter, thereby to vary the speed of said cam as the sphere being wound increases in diameter.

19. In a machine for winding spherical bodies, the combination of a pair of opposed winding heads, sphere driving rollers carried by said heads, said rollers rotating on individual axes which are parallel to each other but at an angle to the axes of said heads, a mount for the rollers of one head, a drive therefor for rotating the mount intermittently about an axis parallel to the axis of said head, said drive including a cam, and means actuated by the recession of one head with respect to the other due to the gradually increasing diameter of the sphere being wound for varying said drive therefor to vary the speed of said cam, to effect a variation in the rotation of said mount in direct ratio to the increase in the sphere diameter.

20. In a machine for winding spherical bodies, the combination of opposed winding heads, sphere engaging rollers carried by said heads, said rollers being rotatable about axes which are at an angle to the axes of said heads, a positive drive for the rollers of one head to rotate said rollers about their own axes, said drive including a drive shaft, a driving disc fixed to said shaft, friction rollers engaging one face of said disc to rotate the same, and means for shifting said rollers on said disc radially thereof to vary the disc speed and hence the speed of said drive shaft.

21. In a machine for winding spherical bodies, the combination of opposed winding heads, sphere engaging rollers carried by said heads, said rollers being rotatable about axes which are at an angle to the axes of said heads, a positive drive for the rollers of one head to rotate said rollers about their own axes, said drive including a drive shaft, a driving disc fixed to said shaft, friction rollers engaging one face of said disc to rotate the same, and means actuated by the sphere being wound to shift said rollers on said

disc radially thereof, thereby to vary the disc speed and hence the speed of the positively driven rollers.

22. In a machine for winding spherical bodies, the combination of opposed winding heads, sphere engaging rollers carried by said heads, said rollers being rotatable about axes which are at an angle to the axes of said heads, a positive drive for the rollers of one head to rotate said rollers about their own axes, said drive including a drive shaft, a driving disc fixed to said shaft, friction rollers engaging one face of said disc to rotate the same, and toggle mechanism actuated by the recession of one head with respect to the other as the sphere being wound increases in diameter to shift said rollers on said disc radially thereof thereby to vary the disc speed and hence the speed of the positively driven rollers.

23. In a machine for winding spherical bodies, the combination of opposed winding heads adapted to receive between them a sphere being wound, sphere engaging rollers carried by said heads, said heads being so mounted that one head will recede from the other as the sphere diameter increases, a drive for the rollers of one head to rotate said rollers on their respective axes, a drive shaft constituting part of said drive, a disc carried by said drive shaft, friction rollers engaging said disc to rotate the same, and toggle mechanism connected to said rollers and to one of said heads whereby as the last mentioned head recedes from the other head, due to the increasing sphere diameter, said rollers will be

shifted radially of said disc thereby to vary its speed and hence the speed of the driven rollers.

24. In a machine for winding spherical bodies, the combination of opposed winding heads, sphere engaging rollers carried by said heads, said heads being in axial alignment, the axes of said rollers being parallel to each other and at an angle to the axes of said heads, a mount for the rollers of each head, means for rotating said mounts intermittently about an axis parallel to the axes of said heads, whereby the axes of the rollers of both heads are maintained in parallelism, and controlling mechanism for said means governed by the sphere being wound whereby the rotation of said mounts will be varied as the sphere diameter increases.

25. In a machine for winding spherical bodies, the combination of opposed winding heads, sphere engaging rollers carried by said heads, the axes of said rollers being parallel to each other but at an angle to the axes of the winding heads, a mount for the rollers of each head, a drive for rotating the rollers of both heads intermittently about axes parallel to the axes of the heads, said drive including a cam carried by each head, and a connection between the heads and said drive to vary the latter thereby simultaneously to vary the speed of said cams to the same extent and in accordance with the increasing diameter of the sphere being wound, so that while the intermittent rotation of the rollers is varied the axes of said rollers will remain in parallelism.
